UNITED STATES PATENT OFFICE.

CARL GABRIELSON, OF SYRACUSE, NEW YORK, ASSIGNOR TO NEWELL MANUFACTURING COMPANY, OF OGDENSBURG, NEW YORK, A CORPORATION OF MAINE.

MACHINE FOR BENDING PIPE.

Application filed June 21, 1922. Serial No. 569,901.

To all whom it may concern:

Be it known that I, CARL GABRIELSON, a citizen of the United States, residing at Syracuse, in the county of Onondaga and State of New York, have invented certain new and useful Improvements in Machines for Bending Pipe, of which the following is a specification.

This invention relates to improvements in machines for bending pipe, and has for its object to provide novel and simple means for forming quarter and other bends on the ends of brass and other tubing. A particular object of the invention is to provide a power-driven mechanism for bending the ends of the thin tubing which comprises the telescoping parts of the well-known extensible curtain rods in common use. And a further object is to improve and simplify the construction, arrangement and operation of pipe-bending machines generally.

I attain these objects by the means set forth in the detailed description which follows and as illustrated by the accompanying drawings, in which—

Figure 1 is a top plan view of the machine ready to start a bending operation. Fig. 2 is an enlarged detailed section, taken substantially on line 2—2 of Fig. 1. Fig. 3 is a front side elevation of the machine. Fig. 4 is a front end elevation of the machine shown in Fig. 1. Fig. 5 is an elevational view of an extensible curtain rod. Fig. 6 is a view of the bending gear. Fig. 7 is respectively an edge and a face view of the locking and bending die. Fig. 8 is a plan view of the circular rack. Fig. 9 is a view showing the position of the working parts at the end of a bending operation. And Fig. 10 is a similar view; showing the manner of ejecting the bent tubing.

In the drawings, 2 represents the base, from which rises an irregular hollow frame, comprising substantially parallel sides 2'—2^a, which virtually inclose and support the whole mechanism. 3 represents the main shaft, to the end 3' of which, a motor (not shown) may be connected, the opposite end being fitted with a hand-wheel 3^a, for use in adjusting the various working parts. The shaft 3 is journalled in the frame sections 2'—2^a. This shaft carries a pinion 3^b, which meshes and drives a relatively large gear 4, the latter being mounted on a shaft

4', which parallels the shaft 3. The gear 4 is provided in its inner face with four or more sockets 4^a, which are preferably spaced equidistantly around the circle, as best seen in Fig. 3. The gear 4 throughout the drawings is shown conventionally for clearness. During the bending operations, the gear 4 is driven constantly through its connection with the shaft 3, and the said gear is arranged to intermittently drive a drum cam 5, which is loosely journalled on the shaft 4', the said drum being operatively connected with the gear 4, by means of a drive-bolt 6, which is reciprocable in a longitudinal socket 6'. The bolt 6 is constantly under the control of a spring 6^a, which exerts its tension for forcing the said bolt towards the gear 4. The bolt 6 carries a stop-pin 6^c, which traverses a slot 6^b in the circumference of the drum 5, the said pin being employed for disengaging the bolt 6 from the sockets of the gear 4, for stopping the drum 5, at the end of each bending operation. The bolt 6 is controlled automatically by a reciprocable cam-bar 8, which is supported by a bracket 8' carried by the frame 2', the said cam-bar being positioned horizontally substantially in line with the axis of the drum 5, and being normally held against the surface of the said drum, by a tension spring 8^a. The free end of the bar 8 is provided with a bevel cam surface 8^b, which is disposed in the path of the stop-pin 6^c, when the bolt 6 and said pin are in the driving position, shown by the full lines in Figs. 1 and 4. The arrows in Figs. 1, 3, 4, 9 and 10 indicate the direction of travel of the gear 4 and the drum 5. At the end of each bending operation the pin 6^c, on reaching the line of the horizontal axis of the drum 5, encounters the cam face 8^b, which forces the pin and the bolt 6 away from the gear 4 sufficiently to break the driving connection between said parts. The drum 5 will then come to a stop due to the pressure exerted by the bar 8, which is under tension of the spring 8^a. The said bolt and pin will then remain in the released position, until the cam-bar 8 is withdrawn, for allowing the spring 6^a to shoot the bolt 6 into the first socket 4^a of the gear 4 that comes into registry with said bolt. The cam-bar 8 is withdrawn by means of a link 9, which connects with the bar by a pin 9', and by a second

link 9^a, whose top end is pivoted to the link 9 at 9^b, the bottom end of link 9^a being rigid on a shaft 9, which extends across the front end of the machine and is fitted with an operating hand lever 9^d. To start the bending operations, the operator swings the lever 9^d, as from the full to the dotted line position, shown in Fig. 1, for freeing the pin 6^c from the cam 8, and starting the rotation of the drum 5, for another revolution, and so on.

The mechanism employed for bending the pipe, as P, will now be described: 10 represents a vertical shaft, which is disposed near the front end of the frame, at right angles to the shaft 4'. Near the bottom end of shaft 10 is mounted a mutilated gear 11, which is made rigid by a key 10'. Immediately above the gear 11, shaft 10 is indirectly supported by a bearing 12 comprising a part of a bracket 12', which may be an integral part of the rear frame portion 2^a. The bearing 12 directly supports a bushing 13, in which the shaft 10 is eccentrically disposed, as best seen in Figs. 1, 9 and 10.

25 The bushing 13 preferably extends from the gear 11 to a point near the top end of shaft 10. Immediately above the bearing 12 is disposed a sleeve 14, and upon this sleeve is rigidly mounted another mutilated gear 15, which with the said sleeve is rotatable on the bushing 13. Directly above the gear 15, the sleeve 14 is enlarged and forms an integral hub 16', of a bending-die bracket 16. The bracket 16 comprises a horizontal arm, 30 which is swingable substantially 90°, during the bending operations, on the sleeve 13 as its axis. The top end of the bushing 13 is supported in a stationary horizontally disposed bracket 17, which is supported by the frame 2^a, and whose inner or free end comprises a circular rack 17' (see Fig. 8). This circular rack is disposed in the same plane as a straight rack 16^a carried by the bracket 16, and the latter rack is arranged to mesh 35 with the rack 17' during the quarter-swinging of the bracket 16, which effects the bending of the pipe P. 18 represents a stationary die, which is provided with a semi-cylindrical mold 18', that conforms to and 40 partially receives the pipe P when it is first inserted in the machine preparatory to the bending of the said end. The die 18 is also supported by the frame 2^a, and its inner end forms a stop against which a shoulder 16^b 45 of the bracket 16 abuts, when the said bracket is in the extended or idle position, shown in Figs. 1, 3, 4 and 10. 16^c represents another straight half-cylindrical die carried by the bracket 16 directly above the 50 rack 16^a, and which aligns with the mold 18' when the parts are in the position, shown in Figs. 1 and 10. 19 represents a locking and bending die, which is substantially diamond-shaped in plan, and which is 55 rigidly secured to the top end of the shaft 60

10. The part 19 is provided with a semi-cylindrical mold for partially receiving the pipe P, the said mold extending in the form of a right-angle curve along two of its margins, which face respectively the rear side 70 and end of the frame, and is disposed directly in line horizontally with the pipe P, both before and during the bending operation, as best seen in Figs. 1 and 10. At the start of the bending operation, the end of 75 the pipe P to be bent, is inserted horizontally between the dies 18 and 19 (while the latter die is in the released position shown in Fig. 10), until the said end of the pipe engages a stop 20 carried by the bracket 16. 80 As the end of the pipe moves inwardly beyond the dies 18 and 19, the pipe telescopically receives the free end of a core-rod or mandrel 21, which supports the said end throughout the bending operation. The 85 core 21 is adjustably supported by the free end 16^d of the bracket 16 by means of nuts 16^e. The core 21 moves with the bracket 16 and serves the dual purpose of supporting and bending the end of the pipe P, as well 90 as that of preventing the collapse, crimping or distorting of the pipe while it is being bent. The bending of the pipe P is effected directly by a segmental gear 22', the latter being an integral part of a relatively long 95 lever 22 and is pivoted at 22^x near the rear end of the frame. The lever 22 and gear 22' are disposed in the same plane as the gear 15, and the segment 22' meshes and drives the said gear in the direction for effecting 100 the bending of the pipe P. The lever 22 is moved from the position shown in Fig. 1, to that shown in Fig. 9, and said lever is swung back and forth in a horizontal plane during and after each bending operation, by 105 the drum cam 5, and for this purpose the said lever is provided with a drive-pin 22^a, which is disposed in and traverses a circumferential cam-groove 23 of the said drum, as best seen in Fig. 3. The drive-pin 22^a 110 is always positioned directly above the axis of the drum 5, and the groove 23 is arranged to move the lever 22 from the position shown in Fig. 1 to that shown in Fig. 9 and thence back to the positions shown 115 in Figs. 1 and 10, during each revolution of the drum 5. In order to carry out the several steps of the bending operation it is necessary that the lever 22 remain stationary while the drum is still rotating, and for this purpose a portion, as 23' of the cam-groove 23, is neutral, as will be understood by consulting Figs. 1, 9 and 10. The drum 5 revolves in the direction of the arrows in Figs. 1, 3, 4, 9 and 10. By referring to Fig. 1, which corresponds to the starting position, it will be understood that the drive-pin 22^a must follow the angular portion 23^a of the groove 23, which carries 120 the lever 22 inwardly. This causes the seg- 125 130

ment 22' to rotate the gear 15, which effects the swinging of the bending bracket 16, as from the full line position in Fig. 1, to that shown in Fig. 9. This effects the bending

5 of the inner end of the pipe P around the right hand edge of the die 19, thereby effecting a quarter bend of the said end, as shown in Fig. 9. As the pipe P is being bent around the die 19, the mandrel 21 is partially withdrawn from the pipe, as shown by dotted lines in Fig. 9. When the lever 22 and the other parts reach the positions, shown in Fig. 9, a second lever 24 of similar construction and arrangement and having a segment gear 24', which meshes with the mutilated gear 11 and which has been temporarily held stationary, as shown in Figs. 1 and 9, starts to swing inwardly towards the longitudinal center of the machine, as from the position shown in Figs. 1 and 9, to that shown in Fig. 10. This inward movement of the lever 24 which is effected by a drive-pin 24^a which plays in a cam-groove 25 of the drum, rotates the shaft 10, and also the die 19 around the axis of the shaft 10. This correspondingly rotates the die 19, which owing to the eccentricity of the axis of the shaft 10 relatively to the axis of the bushing 13, swings the die 19 away from the stationary die 18 (compare Figs. 9 and 10), and frees the pipe P from the latter die. While the lever 24 is being moved inwardly, as described, the lever 22 is carried by the return angular portion 23^c of the groove 23, back towards the neutral part of said groove until said lever reaches the position shown in Figs. 1 and 10. At the end of this latter operation the core 21, and the corresponding end of 40 the pipe P, are again positioned substantially parallel to the aligning dies 18 and 16^c. By the time the lever 24 reaches the position shown in Fig. 10, the stop-pin 6^c encounters the cam-bar 8, which disconnects 45 the bolt 6 from the gear 4 and stops the drum 5. This leaves the lever 24 in the aforesaid operated position. When the die 19 is rotated to the position shown in Fig. 10, the bent tube P is ejected and thrown 50 clear of the machine (see dotted lines in Fig. 10), by an ejecting lever 26, which is pivoted at 26', in the line of the mold of the die 19, (see Figs. 1, 9 and 10). The ejector 26 is thrust outwardly by a pin 27, which is 55 driven by the tension of a spring 27', all of the said parts being disposed in a socket 27^a, of the die 19, as shown in Figs. 1, 4 and 10. After the bent pipe has been ejected, the operator inserts a fresh pipe between the several dies, and again starts the machine by 60 releasing the bolt 6, through the operation of the bar 8, as described.

Obviously pipes of various size, as shown in Fig. 5, may be bent by my machine, by 65 simply providing interchangeable dies, and

by suitably adjusting certain parts of the machine, in a well-known manner.

Having thus described my invention, what I claim, is—

1. In a pipe bending machine, a stationary die, a locking die movable towards and away from the stationary die, a shaft for supporting the locking die, a bending die rotatable on an axis that is eccentric to the axis of the locking-die shaft, gears for intermittently rotating said shaft for first locking and then releasing a pipe, and a train of gears for rotating said bending die while the locking die is held stationary. 70

2. In a pipe bending machine, a plurality of pipe dies, one of said dies being stationary, the other dies being movable, one of the movable dies adapted to hold a portion of the pipe rigid while the other movable die is bending the end of the pipe, 80 said holding die being rotatable on an axis that is eccentric to the axis of the bending die, means for moving the holding die towards and away from the stationary die before and after the bending operation, and means for rocking the bending die towards and away from the holding die. 85

3. In a pipe bending machine, a plurality of pipe dies, one of said dies being stationary, the other dies being movable, one of the movable dies adapted to hold a portion of the pipe rigid while the other movable die is bending the end of the pipe, 90 said bending die being rotatable on an axis that is eccentric to the axis of the holding die, a mandrel carried by the latter die and telescoping the said end, means for moving the holding die towards and away from the stationary die before and after the bending operation, and means for rocking the bending die towards and away from the holding die. 100

4. In a pipe bending machine, a stationary die, a locking die movable towards and away from the stationary die, a shaft for supporting the locking die, a bending die swingable on an axis that is eccentric to the axis of said shaft, a segment gear for intermittently actuating said shaft for first locking and then releasing a pipe, a segment 110 gear for swinging the bending die towards and away from the locking die, and a cylindrical cam for actuating both of said segment gears. 115

5. A pipe bending machine, including a stationary die, a locking die movable towards and away from the stationary die, a shaft for supporting and actuating said locking die, a bending die rockable on an axis which is eccentric to the axis of the locking die, gears for moving the bending die in the direction for bending a pipe while the locking die is stationary, gears for rocking the locking die towards and away from the stationary die, and means for moving 120 125 130

the bending die in the opposite direction while the locking die is being moved in the direction for releasing the pipe.

6. In a pipe bending machine, a stationary die, a locking die movable towards and from the stationary die, a shaft for actuating the locking die, a bending die swingable towards and away from said locking die, gears for intermittently rotating said shaft

10 in opposite directions, gears for intermittently swinging said bending die, and a mandrel telescoping the end of a pipe and movable with the bending die and said end during the rocking movements of said die.

15 7. In a pipe bending machine, a stationary die, a locking die movable towards and away from the stationary die, a shaft for actuating said locking die, a bending die rotatable on an axis that is eccentric to the axis of 20 the locking die, gears for intermittently rotating said shaft for locking and releasing a pipe, a train of gears for rotating the bending die while the locking die is held stationary, a cylindrical cam for actuating 25 all of said gears, means for intermittently operating said cylindrical cam, and means for starting and stopping said cylindrical cam.

8. In a pipe bending machine, a stationary die, a locking die movable towards and away from the stationary die, a shaft for supporting the locking die, a bending die swingable on an axis that is eccentric to the axis of 30 said shaft, a segment gear for intermittently actuating said shaft for first locking and then releasing a pipe, means for ejecting the pipe at the end of said releasing movement, a segment gear for swinging the bending die 35 towards and away from the locking die, and 40 a cylindrical cam for actuating both of said segment gears.

9. In a pipe bending machine, a stationary die, a locking die movable towards and away from the stationary die for locking and 45 releasing a pipe, a shaft for actuating said locking die, a bending die rotatable on an axis that is eccentric to said shaft, means for moving said bending die towards the locking die while the latter is in the locking position, means for moving said bending die 50 in the opposite direction while the locking die is being moved towards the released position.

10. In a pipe bending machine, a stationary die, a locking die movable towards and away from the stationary die for locking and releasing a pipe, a shaft for actuating said locking die, a bending die rotatable on an axis that is eccentric to said shaft, means for 55 moving said bending die towards the locking

die while the latter is in the locking position, means for moving said bending die in the opposite direction while the locking die is being moved towards the released position, a mandrel carried by the bending die for 65 supporting the end of the pipe during the bending operation, and means carried by the locking die for releasing the bent pipe from the said mandrel.

11. In a pipe bending machine, a locking die movable for locking and releasing a pipe, a shaft for supporting said locking die, a bending die rockable towards and away from the locking die, a drum cam, a lever actuated by said cam for rocking said 70 bending die, a second lever actuated by said cam for moving said locking die, a constantly rotating gear, means for operatively connecting said drum cam with said gear, means for starting said drum cam for effecting the 75 locking of a pipe, and means for stopping said drum cam at the end of the bending operation.

12. In a pipe bending machine a constantly rotating member, a drum-cam adapted to 80 be intermittently rotated by said member, means for operatively connecting said drum-cam and said member at the start of the pipe bending operation, means for disconnecting 85 said drum-cam and said member at the end of the bending operation, a locking die movable for locking and releasing the pipe, a shaft for supporting said die, gears for operatively connecting said shaft with said drum-cam, a bending die movable towards and 90 away from said locking die, and gears for operatively connecting said bending die with said drum-cam.

13. In a pipe bending machine, a stationary die, a locking die movable towards and away from the stationary die, a shaft for supporting the locking die, a bending die swingable on an axis that is eccentric to the axis of said shaft, a segment gear for intermittently actuating said shaft for first locking and then releasing a pipe, means carried by the locking die for ejecting the pipe at the end of said releasing movement, a segment gear for swinging the bending die towards and away from the locking die while 100 the latter die is in the locking position, a cylindrical cam for actuating both of said segment gears, means for driving said cylindrical cam, means for stopping said cylindrical cam at the end of the releasing operation, and means for starting said cylindrical cam in advance of each locking operation.

In testimony whereof I affix my signature.

CARL GABRIELSON.
